UNITED STATES PATENT OFFICE.

WILLIAM HENRY MARGETTS, OF TORONTO, ONTARIO, CANADA.

SHADING-MACHINE.

1,348,653.

Specification of Letters Patent. Patented Aug. 3, 1920.

Application filed June 4, 1919. Serial No. 301,685.

To all whom it may concern:

Be it known that I, WILLIAM HENRY MARGETTS, a subject of the King of Great Britain, of the city of Toronto, county of York, Province of Ontario, Canada have invented 5 certain new and useful Improvements in Shading-Machines, of which the following is a specification.

My invention relates to improvements in 10 shading machines, and relates more particularly to the class of shading machine used in connection with lithographing, zincology, and photoengraving, and the objects of my invention are: first, to dispense with all 15 springs or other elastic elements in the adjusting operations of the machine so as to insure absolute accuracy and ease of adjustment; second, to improve the construction so as to require only one adjustment in 20 either direction when adjusting the film frame transversely of the board or stone; third, to adjustably mount the machine on a supporting member whereby it may be coupled to a drawing board, as well as to a 25 table, supporting the stone, and whereby the height of the machine may be adjusted according to the thickness of the stone; fourth, to mount the machine on its supporting member so that it may be bodily shifted 30 transversely of the drawing board or stone, and locked in the desired position, and fifth, to provide means for coupling the film frame to the machine so that notwithstanding the 35 depth of the frame, the same may be positioned to rest flat on the board or stone.

In the following part of the specification, I shall describe my preferred form of construction, and what I claim as new will be pointed out in the claims forming part of 40 this specification.

Figure 1 is a plan view of the shading machine and its supporting member, and clamping plates therefor, showing the same attached to portion of a drawing board and 45 carrying portion of a film frame. Figs. 2 and 3 are vertical cross sections on the lines 2—2, 3—3, respectively, Fig. 1, on an enlarged scale. Fig. 4 is a side elevation of one end of the transverse adjusting means 50 for the film frame. Fig. 5 is a vertical cross section on the line 5—5, Fig. 1. Fig. 6 is an end elevation of the clamping plates and supporting member therefor, showing how the machine may be coupled at the desired 55 height to a table above a stone, and Fig.

7 is a plan view of portion of the coupling clamp for the film frame showing how the same is pivoted to the machine.

In the drawings, like characters of reference refer to the same parts.

In prior machines of this class that I am 60 acquainted with, springs are used in certain adjustments, but since no two springs exert the same power under all conditions, ease and accuracy of adjustment are frequently 65 impaired. Now in adjusting the film frame by my machine, both longitudinally and transversely, I dispense absolutely with any springs, and the consequence is that greater 70 accuracy of adjustment can be secured with consequent improvement in character of work done by the artist.

I omit all keys for the purpose of securing adjustment, and since the movement of 75 one element only is necessary to secure transverse adjustment of the film frame in either direction, I absolutely overcome defects inherent in some classes of machines in making adjustments of this kind.

Broadly considered, the machine 80 comprises front and rear plates; the rear plate being removably coupled to a support, means being associated with said machine at each end of said plates whereby these plates are separated or moved together thereby giving 85 the necessary longitudinal adjustment to the film frame. A threaded adjusting rod is carried by the front plate and dominates the action of a plate mounted to move longitudinally of said front plate, and which is coupled to the film frame. When the machine 90 is embodied in the form illustrated, it is mounted on a supporting member which extends transversely across the drawing board or the stone, and clamping elements are carried by said supporting member whereby the 95 machine is firmly coupled to the drawing board or coupled to a table and supported at the required height above the stone.

When the machine and its supporting 100 members are used with a drawing board, certain means for adjusting the height of the machine above the top of the stone are omitted.

A is the back plate and B the front plate. 105 Secured to each end of the back plate A by any suitable means such as screws C are internally-threaded posts D, which project above said plate. E is the movable supporting member to which the machine is coupled 110

by any suitable means such as a thumb screw F which screws through the hole a, formed in the back plate A, and into the movable supporting member E. A plurality of holes b are formed in the member E so that the thumb screw F may be placed therein and secure the machine in the position it may be moved into longitudinally of the member E. The screws C or other fastening means for the posts D are provided with rounded heads G which extend into a groove H formed longitudinally of the movable supporting member E. The back plate A is provided with a downwardly depending flange I which overlaps the rear side of the movable supporting member E. The flange I, together with the heads G resting in the groove H, permit the machine to be shifted longitudinally on the movable supporting member E readily upon occasion and maintain the machine at right angles to the sides of the drawing board J, for example. While the construction just described is very convenient, it is not absolutely essential. Threaded through each of the posts D is an adjusting screw 2. The forward end of each of the screws 2 is reduced as shown at 3, and is without a thread so as to have bearing in its associated post 4. These posts are coupled by any suitable means such as screws 5 to the plate B. The reduced end of each of the screws 2 projecting beyond the front side of the screws 4 is threaded and receives a circular nut 6, and a lock nut 7. Mounted on each of the posts 2 is an element, such as a nut, which is keyed to the said posts by any suitable means such as a pin 9. Through the co-action of the parts just described, the screws 2 can turn freely in the posts 4 and since these screws are threaded through the posts D by turning the same, the plates A and B may be separated and drawn together the required amount. It will be observed particularly upon referring to Fig. 2, that the circular nuts 6 are provided with a suitable graduated scale bearing appropriate markings. For example, each nut may be marked from zero up to nine. The top side of each post 4 is scored as shown at 7'. These scored markings are placed directly above the longitudinal axis of each adjusting screw 2 so that the graduated scale before referred to may be accurately used so as to secure the desired adjustment at each end of the machine.

8' is an adjusting rod journaled near one end in a plain bearing formed in a bearing block 9'. The other end of the adjusting rod is threaded and operates through a threaded hole (shown by dotted lines in Fig. 1) formed in the bearing block 10. These bearing blocks are secured firmly to the front plate B by any suitable means such as screws 11 extending through lugs 12 forming part of said bearing blocks. The nuts

13 co-act with the said screws to firmly support said bearing blocks to said front bearing.

14 is a plate extending longitudinally of the front plate B and provided at each end with a flange 15 through which extends the adjusting rod 8'. Keyed to each end of the rod 8' and adjacent the outer side of each of the flanges 15 is a nut 16. One of the said nuts is provided with a suitable graduated scale of the character before set forth, so that the film frame 17 (coupled to the adjusting rod 8' by any suitable means, the preferred construction of which will be hereinafter set forth) may be shifted transversely of the drawing board J in either direction. One of the flanges 15 is provided at its top with a scored mark c positioned directly above the longitudinal axis of the adjusting rod 8' so that the graduated scale carried by one of the nuts 16 may be used to secure accuracy of adjustment. It will be observed from the construction described of the adjusting rod 8' and the manner in which the same is coupled to the plate 14 that the said adjusting rod is positively locked against longitudinal movement in the plate 14 while at the same time complete freedom of action is secured to provide for transverse adjustment of the film frame 17 in either direction.

Upon referring particularly to Figs. 3 and 4, it will be observed that a certain portion of the bearing blocks 9' and 10, and the lugs 18 carried thereby have clearance 100 with the plate 14 as shown at 19, thus preventing friction between these elements. In order to prevent any possibility of the plate 14 springing, I preferably mount in each lug 18 a set screw 20, the lower end of 105 which rests easily in a groove 21' formed longitudinally in the plate 14. The friction between the said screws 20 and the plate 14 does not interfere materially with the operation of the rod 8', while this construction 110 or its equivalent possesses the advantage of always maintaining the plate 14 with its front edge in alignment with the front edge of the front plate B in case there should be any tendency for the plate 14 to get out of 115 alignment through the wearing of the bearings of the adjusting rod 8' in the bearing blocks 9' and 10. The holes (not shown) formed in the flanges 15 through which the adjusting rod 8' passes will be of greater 120 diameter than said rod so as to avoid friction.

The film frame 17 may be coupled to the machine by any suitable means: my preferred construction for this purpose comprises a bifurcated arm 21 mounted at each end of the plate 14 and the inner ends of these arms straddle the flanges 15. Bolts 22 couple said arms to said flanges 15 and these bolts are held in place by means of 125

nuts 23. The said bolts and nuts or equivalent means can be used to regulate the ease of movement of said bifurcated arms 21 in respect of the flanges 15.

24 is any suitable clamp provided at each end with tapered pins 25 mounted in lugs 26. At one end of the clamp, one of these tapered pins extends into a socket 27 formed in the inner end of a rod 28 mounted in the outer end of one of the arms 21. A coiled spring 29 on said rod between the socket 27 and its associated arm 21 keeps the rod 28 in position so that the socket 27 will be held against its associated tapered pin 25. A stop 30 carried by the rod 28 limits the movement thereof.

The other end of the clamp 24 is mounted in like manner in its associated arm 21 except that the rod 31 carried by this arm is not spring-held, but is keyed in position by a set screw 32 or equivalent means.

I show a set screw 33 carried by the arm 21 which supports the rod 28 so that if the user of the machine desires, he may positively lock the rod 28 against movement.

The means described as exemplary whereby the machine is coupled to the film frame 17 permits film frames of different thicknesses to be used and at the same time insure that these frames are held flat against their supporting surfaces.

Sufficient has been set forth to show that the artist may inspect the surface of his drawing board or stone by raising the film frame 17 upward around the bearings in which the clamp 24 is mounted and bring it back to original position with the assurance that all points of the film will register with the points on the drawing board or stone that they registered with before the film frame was raised. This will enable the re-inking of any portion of the surface worked upon with accuracy and without danger of impairing any other portion of the work.

45 In order to prevent any tendency of the front plate B to spring above the back plate A, I provide a clamp *d* which is coupled at each end to the plate A by the nuts and screws commonly designated *e*. I desire to make my machine as light as is consistent with accuracy of work and durability, and, therefore, the plates A and B are made quite thin. If these plates be made quite thick, obviously there will be no necessity 55 of using clamp *d* or its equivalent.

The preferred means whereby the supporting member E is coupled to the drawing board J is as follows: 34 and 35 are upper and lower plates between which is clamped 60 the supporting member E. The lower plate 35 is provided with a socket 36 to receive the movable supporting member E so that the upper surface of this supporting member will be flush with the underside of the plate 34. Screwing through the plate 34

are set screws 37 which are jammed against the movable supporting member E to prevent longitudinal displacement of said plates. Screws 38 bind the plates 34 and 35 together as shown clearly in Fig. 5.

The lower plate 35 is provided at each end with a socket 39, which sockets extend through holes 40 (see Fig. 5) formed in the upper plate 34. Clamping means such as described must be positioned near each end 75 of the machine and when the machine is to be clamped to a drawing board as illustrated in Fig. 1, the teeth or spurs 41, projecting beyond the inner edge of the lower plate 35, are forced into the drawing board and then 80 the said screws 37 are tightened up, absolutely insuring the firm support of the machine.

In case it be desired to use my machine in connection with a lithographing stone, I 85 must provide some means whereby the machine is firmly locked to the support or table carrying the stone. My preferred means for this purpose comprises tubular supports 42 substantially of a uniform 90 length and these supports are mounted in the sockets 39. The set screws 43 held in the lower plate 35 of each clamping means maintain the said machine and movable supporting member E at the required height 95 above the top of the table 44 or other suitable support for the stone (not shown). Screws 45 are passed down through each of the tubular supports 42 and screw into the table or other support before mentioned, thereby locking the machine and its movable supporting member E firmly in place. 100

A great advantage derived from the principle of my invention is that the machine may be attached to the drawing board 105 no matter in what angular position the board is in.

While I have described what I consider to be the best embodiment of my invention, I desire it to be understood that the principle may be embodied in different forms, and I desire not to be limited beyond the requirements of the prior art and the terms of my claims.

What I claim as my invention is,

1. A machine of the class described comprising front and back plates; a movable supporting member to which the said back plate is firmly coupled; two adjusting screws, each provided with a suitable graduated scale, positioned one at each end of the said plates; aligned supporting members carried by said plates with which said adjusting screws are adapted to co-act so that said front plate may be moved toward or away from said back plate the same distance at each end; an adjusting rod provided with a suitable graduated scale, and threaded at one end, and extending at each end through a movable plate positioned above said front 120 plate.

plate, and means carried by said front plate in which said adjusting rod has bearing and with which the thread of said rod co-acts in order that said movable plate may 5 be shifted longitudinally of said front plate in either direction.

2. A machine of the class described comprising front and back plates; a movable supporting member to which said back plate 10 is firmly coupled; two adjusting screws, each provided with a suitable graduated scale, positioned one at each end of the said plates; alined supporting members carried by said plates with which said adjusting 15 screws are adapted to co-act so that said front plate may be moved toward or away from said back plate the same distance at each end; an adjusting rod provided with a suitable graduated scale, and threaded at 20 one end, and extending at each end through a movable plate positioned above said front plate; means carried by said front plate in which said adjusting rod has bearing and with which the thread of said rod co-acts in 25 order that said movable plate may be shifted longitudinally of said front plate in either direction, and clamping means removably carried by each end of said movable supporting member and adapted to 30 firmly couple said movable supporting member to the body above which said movable supporting member and machine are positioned.

3. A machine of the class described comprising front and back plates; a movable supporting member to which said back plate 35 is firmly coupled; two adjusting screws each provided with a suitable graduated scale, positioned one at each end of said plates; alined supporting members carried by said plates with which said adjusting screws are 40 adapted to co-act so that said front plate may be moved toward or away from said back plate the same distance at each end; an adjusting rod provided with a suitable 45 graduated scale, and threaded at one end, and extending at each end through a movable plate positioned above said front plate; means carried by said front plate in which 50 said adjusting rod has bearing and with which the thread of said rod co-acts in order that said movable plate may be shifted longitudinally of said front plate in either direction, and clamping means removably 55 carried by each end of said supporting member and adapted to firmly couple said supporting member to the body above which said supporting member and machine are positioned, each comprising upper and 60 lower plates adapted to be clamped to said movable supporting member; a pair of sockets carried by the lower of said plates and extending through holes formed in the upper of said plates; a tubular support 65 adapted to be mounted in each of the said

sockets; means whereby said tubular supports are locked in said sockets so as to support said machine and its movable supporting member at the desired height above the surface worked upon, and means operating 70 through said tubular supports whereby the machine and its movable supporting member are firmly coupled to a support.

4. A machine of the class described comprising front and back plates; a pair of internally-threaded posts carried by said back plate and positioned one at each end thereof; a pair of bearing posts carried by said front plate and positioned one at each end thereof and each in alinement with its associated 75 internally-threaded post; an adjustable screw mounted in each of the said threaded posts and extending through the said bearing posts; a nut carried by the inner end of each of said adjustable screws and each provided 80 with a suitable graduated scale; means whereby said adjustable screws are rotatably mounted in said bearing posts and held against longitudinal movement therein so that when said adjustable screws are turned, 85 the said plates may be separated the same distance at both ends; an adjusting rod threaded at one end; a pair of bearing blocks carried by said front plate through which said adjusting rod extends and with one of 90 which it has threaded engagement; a movable plate through which each end of said adjusting rod extends; a nut provided with a graduated scale carried by said adjusting 95 rod and co-acting with means carried by the 100 other end of said rod and with said movable plate whereby said movable plate may be shifted longitudinally of said front plate in either direction, and a supporting member whereby said back plate is clamped in position. 105

5. In a machine of the class described, in combination a back plate provided at its rear side with a flange depending therebelow; a grooved movable supporting member to 110 which said back plate is firmly coupled and against which said flange abuts; a pair of internally-threaded supporting members positioned one at each end of said back plate and each with its vertical axis in alinement with 115 the longitudinal center of the groove formed in said movable supporting member; means coupling said internally-threaded supporting members to said back plate and depending therebelow and into the said groove; a 120 front plate; a pair of alined bearing members carried by said front plate one at each end thereof; adjusting screws threaded through said internally-threaded supporting members and having bearing at their forward ends in the bearing members carried by said front plate; means whereby the forward ends of said adjusting screws are 125 allowed rotary movement in said bearing members and held against longitudinal move- 130

ment therein, the whole designed to coöperate as set forth.

6. In a machine of the class described, in combination a base plate; a second plate extending longitudinally of said base plate and operating above the same and provided at each end with an upturned flange; a pair of bearing blocks carried by said base plate and overhanging said second-mentioned plate 5 and having clearance therewith; an adjusting rod mounted in said bearing blocks and provided with a thread at one end for engagement with a threaded hole in one of said bearing blocks; the said adjusting rod 10 projecting through the said flanges; finger pieces associated with each end of said adjusting rod and operating against the outer side of each of the said flanges, one of said finger pieces being provided with a graduated scale so that said second-mentioned plate 15 may be shifted longitudinally in either direction, and set screws carried by the forward portions of said bearing blocks which overhang said second-mentioned plate and 20 are designed to rest in a groove formed longi- 25

tudinally of said second-mentioned plate, as set forth and for the purpose specified.

7. In a shading machine, in combination a supporting member; clamping means mounted at each end thereof comprising 30 upper and lower plates; the said lower plate being provided with a socket to receive said supporting member and said upper plate being provided with holes; sockets carried by said lower plate and projecting through the 35 holes formed in said upper plate; means whereby said plates are removably coupled together; means whereby said clamping means are clamped to said supporting member in the desired position; tubular supports 40 mounted in each of the said sockets to regulate the height of the supporting member above the surface operated upon; means whereby said clamping means are locked to said tubular supports, and means extending 45 through said tubular supports whereby said supporting member may be firmly coupled to a table top.

WILLIAM HENRY MARGETTS.
